MARSHALL CORNINE, OF MOUNT VERNON, AND ALFRED HAKANSON, OF BRONX, NEW YORK, ASSIGNORS TO CORNINE-HAKANSON DIE CASTING CO., INC., OF NEW YORK, N. Y., A CORPORATION OF NEW YORK

COIN CONTROLLED MECHANISM

Original application filed February 23, 1929, Serial No. 341,952. Divided and this application filed August 16, 1930. Serial No. 475,692.

This invention relates to coin controlled mechanisms and is a division of our co-pending application Serial No. 341,952, filed Feb. 23rd, 1929.

5 Experience in actual operation of vending machines has shown that they get out of order owing to hard usage by the public and that it is frequently necessary to repair and replace the coin controlled mechanisms.

10 Therefore, one object of the invention is to provide an extremely simple form of construction mounted entirely on one removable plate which may readily be attached to the front wall of a vending machine casing.

15 A further object of the invention is to provide a construction wherein the parts are easily removable so that a broken part may be quickly removed and a new part inserted with simple tools and without the necessity of 20 taking the entire mechanism to the shop for repairs.

A further object is to provide a construction wherein the goods dispensing mechanism will be positively locked against operation 25 unless and until a proper coin is inserted in the coin mechanism.

The invention consists in the combination, construction and arrangement of parts as herein illustrated, described and claimed.

30 In the accompanying drawings, forming part hereof, is illustrated one form of embodiment of the invention, in which drawings similar reference characters designate corresponding parts, and in which:

35 Figure 1 is a rear elevation, partly broken away;

Figure 2 is a vertical section, taken approximately on line 2—2 of Figure 1, looking in the direction indicated by the arrows; and,

40 Figure 3 is a composite view showing the construction of the operating shaft and collar.

Referring to the drawings A designates a portion of the front wall of a vending machine which is provided with an opening into 45 which is removably inserted a panel 12. The panel 12 is provided with side flanges 13 and carries all of the mechanism hereinafter referred to.

The mechanism is operable from the outside of the casing by means of a handle 42

which is secured to an operating shaft 41. On the shaft 41 adjacent the panel 12 is secured a collar 40. The collar 40 is provided with an eccentric portion 40a and a flat surface 40b. Adjacent the flat portion 40b the 55 collar 40 is provided with a recess 51.

The inner end of the shaft 41 terminates in a bifurcated boss 43 which is adapted to engage the end 41a of a shaft to operate any kind of dispensing apparatus operable by rotation of the shaft. 60

A circular boss 44 is disposed on the panel 12. An offset lever 45 is pivoted on the boss 44 and is provided with a flange 46. The flange 46 is adapted to strike a coverplate 57, 65 hereinafter described, to limit the range of movement of the lever 45. On the lower end of the forward face of the lever 45 is a lug 47 which is adapted to act as a coin holder. A second lever 48 is also pivoted on the boss 44 behind the lever 45. The lever 48 has a vertical flange on its forward face in alignment with the lug 47 on the lever 45 so that when a proper coin is inserted it will be held 70 between the lug 47 and the flange 49. 75

Centrally of its length the lever 48 has a shoulder 50. When the mechanism is in normal position the shoulder 50 lies in the path of movement of the top wall of a recess 51 on the collar 40 on the shaft 41. The normal distance between the shoulder 50 and the recess 51 is such that the shaft 41 may be turned approximately 20° before the shoulder 50 engages in the recess 51 and prevents further movement. When in this position 80 the lever 45 is against the flat surface 40b of the collar 40. 85

The levers 45 and 48 are held against the collar 40 by means of a leaf spring 52 which is inserted between the levers 45 and 48 and one edge flange 13 on the panel 12. The upper end 53 of the spring 52 engages in a lug 54 on the lever 45 and the lower end 55 of the spring 52 engages in a recess 56 in the lever 48, thus holding both the levers 45 and 48 yielding against the collar 40. The lever 45 is in contact with the forward portion of the collar 40, that is, the portion nearest the panel 12 and the lever 48 is in contact with the central portion of the collar 40. The por- 90 95 100

tion of the collar 40 against which the lever 48 is pressed is not eccentric. A cover plate 57 holds the levers 45 and 48 and the spring 52 in place. The plate 57 is held by means of a stud 58 which passes through the plate 57 and into a boss 59 on the panel 12.

On one side of the panel 12 is disposed a coin box 60 which is provided with a hinged door 61. The portion of the coin box 60 which is directly below the lower ends of the levers 45 and 48 is provided with an opening 62, through which the coin may be dropped as hereinafter described.

On the front face of the panel 12 is provided a coin insertion opening 65 through which coins may be inserted. Beneath the opening 65 is a slug and washer detecting mechanism as described in the original application of which this is a division. When a coin passes the slug and washer detector it will strike the inclined runway 20a, will roll downward and lodge between the lug 47 and the flange 49.

The hook 75 and the flanges 74 are used, in conjunction with other means, to secure the wall A to the vending machine casing.

Operation

A cycle of operation of the mechanism is as follows: If a proper coin C is inserted in the opening 65 it will pass through the slug and washer detector, strike the inclined runway 20a and be held between the lug 47 and the flange 49. If the coin is an improper one it will be ejected from the machine before it reaches the levers 45 and 48. When the coin C has been inserted, the handle 42 is turned in the direction indicated by the arrow. The handle 42 rotates the shaft 41 and the collar 40. As the collar 40 begins to rotate the lever 45 is moved toward the left hand by the cam action of the collar 40. The coin C, being lodged between the lug 47 on the lever 45 and the flange 49 on the lever 48, forces the lever 48 toward the left. This movement of the lever 48 moves the shoulder 50 from the path of movement of the top wall of the recess 51 so that the collar 40 may make a complete revolution. After the shoulder 50 is moved out of the way of the recess 51 it is carried by the pressure of the coin C to the dotted line position of Figure 1. At this point the eccentric portion 40a of the collar 40 is presented to the lever 45 and the lever 45 begins to retreat toward the right hand side of Figure 1. The lever 48, riding against the non-eccentric portion of the collar 40, stays in the dotted line position until a complete revolution of the shaft 41 has been made. As the lever 45 retreats toward the right hand, the space between the levers widens so that the coin C is released and drops through the opening 62 into the coin box 60. When the collar 40 has made a complete revolution, the

levers 45 and 48 are in their normal position and the mechanism is ready for the next operation.

Having thus fully described the invention, what is claimed as new and desired to be secured by Letters Patent is:

1. A coin controlled mechanism comprising a shaft, an operating collar provided with a recess disposed on the shaft, a pair of superposed coin gripping levers disposed against the collar, one lever having a shoulder to engage in the recess and means to operate the shaft to move the coin gripping levers. 75

2. A coin controlled mechanism comprising a shaft, an operating collar provided with a recess disposed on the shaft and provided with an eccentric portion, a pair of superposed coin gripping levers disposed against the collar, one lever having a shoulder to engage in the recess and means to operate the shaft to move the coin gripping levers. 80

3. A coin controlled mechanism comprising a shaft, an operating collar provided with a recess disposed on the shaft and provided with an eccentric portion, a pair of superposed coin gripping levers disposed against the collar, one lever having a shoulder to engage in the recess, means to hold a coin between the levers and means to operate the shaft to move the coin gripping levers. 85 90

4. A coin controlled mechanism comprising a shaft, an operating collar provided with a recess disposed on the shaft, one lever having a shoulder to engage in the recess, a pair of superposed coin gripping levers disposed against the collar, means to hold a coin between the levers comprising a lug on one lever and a flange on the other lever and means to operate the shaft to move the coin gripping levers. 100 105

5. A coin controlled mechanism comprising a shaft, an operating collar provided with a recess disposed on the shaft, a pair of superposed coin gripping levers disposed adjacent the collar, one lever having a shoulder to engage in the recess and a spring to hold the levers yieldingly against the collar. 110

6. A coin controlled mechanism comprising a supporting panel, a shaft disposed through the panel, an operating collar provided with a recess disposed around the shaft, a pair of superposed coin gripping levers disposed adjacent the collar, one lever having a shoulder to engage in the recess, a spring to hold the levers yieldingly against the collar 115 120 and a cover plate to hold the levers and the spring against the panel.

7. A coin controlled mechanism comprising a shaft, an operating collar provided with a recess disposed on the shaft and provided with an eccentric portion, a pair of superposed coin gripping levers disposed against the collar, one lever having a shoulder to engage in the recess, means to hold a coin between the levers, means to operate the shaft to move 125 130

- the coin gripping levers and a coin receptacle disposed beneath the lower ends of the levers to receive the coins as released by the levers.
8. In a coin controlled mechanism a supporting and actuating member, a collar surrounding the actuating member and provided with an eccentric portion and a recess and a pair of superposed levers disposed adjacent the collar, one lever being disposed against the eccentric portion and the second lever being disposed adjacent the recessed portion of the collar and provided with a shoulder adapted to engage in the recess.
9. In a coin controlled mechanism a supporting and actuating member, a collar surrounding the actuating member and provided with an eccentric portion and a recess, a pair of superposed levers disposed adjacent the collar, one lever being disposed against the eccentric portion and the second lever being disposed adjacent the recessed portion of the collar and provided with a shoulder adapted to engage in the recess to prevent rotation of the actuating member.
10. In a coin controlled mechanism a supporting and actuating member, a collar surrounding the actuating member and provided with an eccentric portion and a recess, a pair of superposed levers disposed adjacent the collar, one lever being disposed against the eccentric portion and the second lever being disposed adjacent the recessed portion of the collar and provided with a shoulder adapted to engage in the recess to prevent rotation of the actuating member and means to hold a coin between the levers to disengage the shoulder from the recess upon movement of the collar.
11. In a coin controlled mechanism a supporting and actuating member, a collar provided with a recess surrounding the supporting member, a pair of superposed levers disposed adjacent the collar, one lever having a shoulder to engage in the recess, means on the levers to hold a coin, means operated by movement of the supporting member to move the levers in one direction and means to retract one lever to release a coin.
12. In a coin controlled mechanism a supporting and actuating member, a collar provided with a recess surrounding the supporting member, a pair of superposed levers disposed adjacent the collar, one lever having a shoulder to engage in the recess, means on the levers to hold a coin, means operated by movement of the supporting member to move the levers in one direction comprising an eccentric portion on the collar and means to retract one lever to release a coin comprising a spring pressed against the lever.
13. In a vending machine, in combination with a removable panel, a coin controlled mechanism carried entirely by the panel comprising a supporting and actuating member, a collar provided with a recess surrounding the supporting member, a pair of superposed levers disposed adjacent the collar, one lever having a shoulder to engage in the recess, means on the levers to hold a coin, means operated by movement of the supporting member to move the levers in one direction and means to retract one lever to release a coin.
14. In a vending machine, in combination with a removable panel, a coin controlled mechanism carried entirely by the panel comprising a supporting and actuating member, a collar provided with a recess surrounding the supporting member, a pair of levers disposed adjacent the collar, one lever having a shoulder to engage in the recess, means on the levers to hold a coin, means operated by movement of the supporting member to move the levers in one direction comprising an eccentric portion on the collar, means to retract one lever to release a coin comprising a spring pressed against the lever and a cover plate to hold the spring and the levers against the panel.
- In testimony whereof they have both affixed their signatures.
- MARSHALL CORNINE.
ALFRED HAKANSON.
